UNITED STATES PATENT OFFICE

ERNEST A. KAHLE, OF CHICAGO, ILLINOIS

DESIGN FOR A BOX FOR CONFECTIONERY AND OTHER MERCHANDISE

Application filed April 4, 1932. Serial No. 43,384. Term of patent 3½ years.

To all whom it may concern:

Be it known that I, ERNEST A. KAHLE, a citizen of the United States, residing at Chicago, in the county of Cook and State of Illinois, have invented a new, original, and ornamental Design for a Box for Confectionery and Other Merchandise, of which the following is a specification, reference being had to the accompanying drawings, forming a part thereof.

In the drawings:

Figure 2 is a perspective exhibiting in detail the manner in which the sections of the box may be swung apart by virtue of the hinge connections therebetween.

I claim:

The ornamental design for a box for confectionery and other merchandise, substantially as shown and described.

Chicago, Illinois, March 28, 1932.

ERNEST A. KAHLE.
